UNITED STATES PATENT OFFICE

164,705

COMBINATION HAMMER, NAIL-EXTRACTING CLAW, AND WRECKING TOOL

Henry Thomas Moses, Fulton, N. Y., assignor to
William B. Colitre, Fulton, N. Y.

Application October 26, 1950, Serial No. 12,742

Term of patent 14 years

(Cl. D54—13)

To all whom it may concern:

Be it known that I, Henry T. Moses, a citizen of the United States, residing at Fulton, in the county of Oswego and State of New York, have invented a new, original, and ornamental Design for a Combination Hammer, Nail-Extracting Claw, and Wrecking Tool, of which the following is a specification, reference being had to the accompanying drawing, forming part thereof.

Fig. 1 is a side elevational view of a combination hammer, nail-extracting claw, and wrecking tool, showing my new design.

Fig. 2 is a front elevational view.

Fig. 3 is a rear elevational view.

Fig. 4 is a top plan view.

The dominant feature of this design is the relative position of the hammer poll with respect to the nail-extracting claw extension of shallow arcuate shape, and to the tool shank, the poll projecting from the shank at the juncture between the shank and nail-extracting claw

extension and the axis of the poll slanting away from the shank so that the face of the poll is in a plane in acute angular relation to the axis of the shank, all as shown.

I claim:

The ornamental design for a combination hammer, nail-extracting claw, and wrecking tool, as shown and described.

HENRY THOMAS MOSES.
